UNITED STATES PATENT OFFICE.

PETER B. HANSEN AND MELVIN HANSEN, OF VIBORG, SOUTH DAKOTA.

WHIP-ACTUATING DEVICE.

Application filed December 6, 1923. Serial No. 678,945.

To all whom it may concern:

Be it known that we, PETER B. HANSEN and MELVIN HANSEN, citizens of the United States of America, residing at Viborg, in the county of Turner and State of South Dakota, have invented certain new and useful Improvements in Whip-Actuating Devices, of which the following is a specification.

This invention relates to new and useful improvements in whip actuating devices.

An important object of the invention is to provide a device to which whips may be attached for permitting the latter to be actuated by a person positioned a considerable distance therefrom.

A further object of the invention is to provide a whip actuating device which may be mounted on the tongue of a sulky or gang plow, adjacent to the lead horses, for permitting a person on the driver's seat to make such lead horses do their share of the pulling.

A further object of the invention is to provide a device of the above mentioned type which is of extremely simple construction and one that may be manufactured at a very nominal cost.

Other objects and advantages of the invention will be apparent during the course of the following description.

In the accompanying drawing forming a part of this specification and in which like numerals are employed to designate like parts throughout the same,

Figure 1 is a top plan view of the whip actuating device embodying this invention.

Figure 2 is a side elevational view of the device shown in Fig. 1.

Figure 3 is a fragmentary rear elevational view, partly in section, of the device shown in Figs. 1 and 2, and

Figure 4 is a vertical sectional view showing a fragmentary portion of the device and taken upon line IV-IV of Fig. 3.

In the drawing, wherein for the purpose of illustration is shown a preferred embodiment of this invention, the numeral 5 designates a reversely bent supporting bracket having suitable apertures 6 formed in its inner end which permit the said supporting bracket to be suitably secured to the tongue of a sulky or gang plow, adjacent to the lead horses. The elevated section 5^a of the reversely bent supporting bracket 5 has suit-

ably attached thereto as by the rivets 7, a transversely extending bar 8 which is provided with perpendicularly extending end portions 9 which act as stops for the whip carrying arms which will be described at a later point. The upper end section 5^a of the reversely bent supporting bracket 5 is provided with a suitable aperture 10 which is adapted for receiving the bolt 11, as best illustrated in Fig. 4. The washer 12 is interposed between the head of the bolt 11 and the surface of the end section 5^a positioned adjacent thereto.

This bolt 11 is adapted for pivotally supporting the whip carrying arms 13 and 14 which are retained in spaced relation to each other by means of the spacer element 15 while the lower whip carrying arm 14 is retained in spaced relation to the bracket end sections 5^a by means of the spacer element 16. An additional washer 17 is interposed between the upper space of the upper whip carrying arm 13 and the inner face of the nut carried by the bolt 11, as illustrated. It will be seen by this construction that the whip carrying arms 13 and 14 will be permitted to freely rotate upon the bolt 11. It will also be seen, by inspecting Figs. 1 and 3, that the said whip carrying arms 13 and 14 are pivotally connected to the bolt 11 at points suitably spaced inwardly from their inner ends. By inspecting Figs. 1 to 3 inclusive, it will be seen that these whip carrying arms 13 and 14 are provided with suitably spaced apertures positioned adjacent their outer ends which are adapted for receiving the hook-shaped clamping bolts 19 by means of which the handle ends 20 of the whips may be secured to the said arms.

Suitably secured to the intermediate portion of the reversely bent supporting bracket 5, as by the lock nuts 21 is a perpendicularly extending eye bolt 22 which is of angular formation and is provided with the depending pair of pulleys 23, as best illustrated in Figs. 1 and 2. Suitably attached to the inner ends of the upper and lower whip carrying arms 13 and 14 as at 13^a and 14^a, are the cables 24 and 25 which pass over the pulleys 23 and extend rearwardly to the driver's seat. It will be seen by this construction, that when the cable 24 is pulled by the driver, the upper whip carrying arm 13 will be swung or pivoted upon the bolt 11 in

the direction of the arrow shown in Fig. 1 and that when the cable 25 is pulled upon, the lower whip carrying arm 14 will be pivoted or swung forwardly in the direction of the arrow illustrated in Fig. 1. For the purpose of returning these arms 13 and 14 to their normal inoperative positions against the perpendicular stop elements 9, the upper whip carrying arm 13 is suitably connected 10 to the tension spring 26, as at 13^b which is positioned outwardly of the fulcrum point of the said arm 13. This tension spring 26 is connected at its other end to the eye of the angular bolt 22. The lower whip carrying arm is connected to the tension spring 27, as at 14^b which is spaced outwardly of the fulcrum point of the said lower arm 14. This tension spring 27 is also connected at its free end to the eye of the angle bolt 22.

20 The operation of the device is as follows:—

It is to be understood that the reversely bent supporting bracket 5 is to be mounted upon the end of the tongue of a sulky or 25 gang plow rearwardly of the lead horses. When the driver desires to cause the right hand lead horse to pull harder than the left hand horse or in other words desires to whip the right hand horse, he pulls upon the cord 30 24 which actuates the whip carrying arm 13. In a similar manner, when the driver desires to whip the left hand lead horse, he pulls upon the cable 25 which will actuate the lower whip carrying arm 14. When the 35 pulling force has been released from the cables 24 and 25, the tension springs 26 and 27 respectively will return the whip carry-

ing arms 13 and 14 to their normal inoperative positions against the stops 9.

It is to be understood that the form of this invention herewith shown and described is to be taken as the preferred example of the same, and that various changes in the shape, size, and arrangement of parts may be resorted to without departing from the spirit 45 of the invention or the scope of the subjoined claim.

Having thus described the invention, we claim:—

In a device of the type described, a reversely bent supporting bracket, an upright fastened to one end of said bracket, upper and lower arms pivoted on said upright, hook-shaped whip clamping bolts carried by each arm, a perpendicularly extending angular eye bolt connected to the intermediate portion of the reversely bent bracket, a spring connected to each arm outwardly of its pivot point and to the eye of said bolt, a transversely extending bar mounted on the 60 end of the bracket to which said upright is fastened and having perpendicular end portions adapted to engage the ends of the arms for limiting their movements in the direction they are pulled by said springs, a pair 65 of pulleys connected to the eye of said bolt, and a flexible cord attached to the inner end of each arm and passing over said pulleys for permitting the arms to be moved against the pull of said springs.

In testimony whereof we affix our signatures.

PETER B. HANSEN.
MELVIN HANSEN.
